UNITED STATES PATENT OFFICE.

FREDERICK B. MALLORY, OF PORTLAND, OREGON.

DESIGN FOR A CROSS-HEAD FOR BLOCKS.

45,911.

Specification for Design.

Patented June 9, 1914.

Application filed March 8, 1913. Serial No. 753,099. Term of patent 14 years.

To all whom it may concern:

Be it known that I, FREDERICK B. MALLORY, a citizen of the United States, residing at Portland, in the county of Multnomah and State of Oregon, have invented a new, original, and ornamental Design for a Cross-Head for Blocks, of which the following is a specification, reference being had to the accompanying drawing, forming part thereof, in which the figure is a perspective view of my design.

The design consists of two links 1, with perforations 2, passing through each end thereof; said links being connected by spreader 3 which is integral with the links. The spreader conforms in horizontal configuration to the longitudinal lines of the

edges of the links, while the other two sides are perpendicular with rounded corners which are tangent with the horizontal portions of said spreader. The longitudinal edges of links 1 consist of arcs which are tangent with the semicircular edges of said links.

I claim:—

The ornamental design for a cross-head for blocks, substantially as shown and described.

In testimony whereof, I hereunto affix my signature in the presence of two witnesses.

FREDERICK B. MALLORY.

Witnesses:

M. A. KELLYHER,
G. F. HICKOK.
